(57) **CLAIM**

The ornamental design for a comb as shown and described.

DESCRIPTION

FIG. 1 is a front, top, left side perspective view of a comb showing my new design;

FIG. 2 is a rear, bottom, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of illustrating portions of the comb that form no part of the claimed design.

The dot-dashed broken lines which define the bounds of the claimed design form no part of the claimed design.
